WALL RACK

Frances L. Ferguson, Lagrange, Ind.

Application April 10, 1952, Serial No. 19,277

Term of patent 14 years

(Cl. D33—3)

To all whom it may concern:

Be it known that I, Frances L. Ferguson, a citizen of the United States, residing at Lagrange, in the county of Lagrange and State of Indiana, have invented a new, original and ornamental Design for a Wall Rack, of which the following is a specification, reference being had to the accompanying drawing, forming part thereof.

Figure 1 is a perspective view of a wall rack, showing my new design, and

Figure 2 is a sectional view, taken substantially in the plane of the line 2—2 in Figure 1.

I claim:

The ornamental design for a wall rack, as shown.

FRANCES L. FERGUSON.
